[57] ABSTRACT

An apparatus for lifting drums off a conveyor and rotating them while they are either labeled or printed on. A converging, horizontally disposed group of conical rollers arranged in a hub and spoke configuration are lifted at their hub or tip end so as to lift the drum off of conveyor rollers and a pair of opposing and horizontally positioned driven belt conveyor systems which converge on the drum to rotate it past an inking printer and/or labeler.

FIG. 5

DRUM POSITIONING AND PRINTING APPARATUS

This invention relates to an apparatus for lifting circular containers or drums off of a conveyor and for rotating them by a rotary printer and/or labeler.

In the general process of filling containers or drums one of the important steps is the labeling or printing of the filled container.

Most container handling systems today use some form of conveying means to transport the containers or drums during the filling, sealing and labeling operations.

A problem encountered in labeling is how to take the moving drum, stop it and label it in a fast, economical and efficient manner.

Since the containers or drums are moving in a liner direction it is difficult to print completely around the circumference of the drums.

Conventional methods of printing or labeling a drum on a conveyor generally comprise applying the label to only one side thereof. This technique renders subsequent identification of the drum in a warehouse quite difficult particularly when it has been palletized or otherwise multi-unit stored.

The present invention is designed to overcome all of these problems previously encountered and enumerated above. According to the instant invention, an apparatus is provided which performs the following sequences:

The drum is sensed by a photocell. When in position a lift platform lifts the drum clear of the conveyor and an air cylinder is energized to move the drum turner into the drum. When pressure builds up on the drum turner cylinder indicating the drum turner is against the drum this resets by a pressure switch the printer rotation counter and turns on the drum turner drive. The printer assemblies are moved into contact with the turning drum and a proximity switch with a cam mechanism counts the rotations of the drum print wheel. When four revolutions have been counted the operation is topped. The printers are removed from the drum, the drum turner drive is stopped and retracted, and the drum lift lowers the drum back onto the conveyor.

Accordingly, it is an object of the present invention to provide an automatic apparatus for lifting drums from a conveyor, centering and rotating them as desired for printing and/or labeling.

Another object of the present invention is to provide an apparatus to lift drums off roller conveyors and to rotate them while engaged with a printer for a predetermined amount.

A further object of this invention is to provide an apparatus for stopping containers being transported by conveying means and printing information on the circumferences thereof.

These and other objects of the present invention will become apparent when taken with reference to the accompanying specification and drawings in which:

FIG. 1 is a side elevational view of the printers used in this invention looking along the direction of movement of the drums;

FIG. 2 is a partial front elevational view of the apparatus shown in FIG. 1 showing one of the printer mechanisms;

FIG. 3 is a plan view of the general arrangement of the lifting mechanism and drum rotating apparatus of the present invention;

FIG. 4 is a plan view of the apparatus similar to FIG. 3 showing the lifting and rotating mechanisms in greater detail;

FIG. 5 is a side elevational view of the arrangement shown in FIG. 4 with the drum lifting apparatus in the up position, and

FIG. 6 is a partial front elevational view of the mechanism shown in FIG. 5.

Referring now to FIG. 1, there is shown the drum printing apparatus designated generally as 100.

A horizontally disposed support member 101 supports an L-shaped rail 101' and a C-shaped rail 102 for supporting conventional rollers R₁. A safety guard 103 extends over the end of the rollers covering the roller chain sprockets, such as 104, for engaging a driving chain (not shown).

On one side of the conveyor is a pair of vertical support members 105 and 106 which are slidable and adjustably secured together in any suitable manner such as bolts 106'.

Mounted atop member 106 is a housing 107 having an enclosing flange 108. On the reverse side of the housing is mounted an air cylinder 109. Through a crank arrangement designated generally as 110 in FIG.

1, the motor 116 rotates an arm 111 through a given arc which rotates a shaft 114 held in journals 113 which are secured to the housing by brackets 112. A larger diameter section 115 of shaft 114 is connected to one of a series of inker rollers, like 119, which are driven by printer friction wheels engaging the side of a drum. A cover plate 117 and bottom plate 118 are disposed over and under the rollers.

The other side of member 101 has a pair of vertically adjustable members 120 and 121, similar to 105 and

40 106, and braced by plate 122 which support a housing 124 which has a compressed air cylinder 125 secured thereto by bolts 126 (as shown in FIG. 2). A rod 127 is connected to cylinder 125 and, through clevis 128 turns an arm 129 which is fixedly secured to shaft 130.

45 The rotation of shaft 130, rotates the entire printer and inker roll assembly into contact with the circumference of a drum. Shaft 130 is held in place on housing 124 by journals 131 and brackets 132. Cover plates 134 and 50 136 are mounted above printer roller 133 and the accompanying inker rollers.

It should be noted that the specific inker and printer roller arrangements shown form no part of this invention but are standard items.

55 Referring now to FIG. 3 there is shown the inker and printer roller arrangements in plan view together with the drum lifting apparatus generally designated as 200.

Apparatus 200 consists of a rectangular frame 201 which underlies the conveyor roller frame rails 101 and 103.

Equidistant between rails 101 and 103 are a pair of raised pivot blocks 204 and 206. An identical pair exist in the cross portions of the frame 201.

65 Mounted on plates 211 through 214 are a series of four short roller rails 207 through 210. Between these short rails and rails 101 and 103 are a group of shortened rollers R₂.

A square base plate 215 is located centrally of the roller framework. A block 216 is mounted on this plate and is adapted to be thrust vertically by a vertically disposed air cylinder underneath (not shown).

Extending from block 216 on each of its four sides are a pair of shafts 217 and 218. Mounted for rotation on these shafts are rollers 219 and 220.

Referring now for a moment to FIG. 4, there are shown the four conical rollers, designated as R_3 which act to support the base flange of drum D as the block 216 is raised.

The tip of each roller R_3 has a small bearing surface 222 which is adapted to engage rollers 219 and 220 as the drum revolves and rollers R_3 turn. Each roller R_3 has a conical surface 221 and an annular locking flange portion 223 in which a shaft 224 with a cam follower mounted in its end is received for rotation therein. The end of shaft is pinned (FIG. 5) to portions 206 and 204 of frame 201 and allows the conical rollers to pivot upwardly as the block 216 is raised so that the top surface of the conical rollers are essentially horizontal and above the conveyor rollers.

A pair of cross frame members 231 and 232 are secured across frame 201 and have flange tabs 234 attached thereto. Each tab 234 has a pin 235 secured thereto on which is pivotally mounted a crank arm 236. Pivotally attached to pins 237 and 238 on crank arm 236 are clevis members 239 and 239' which are adjustably mounted on rods 240 240'.

The ends of rods 240 and 240' have adjustable clevis members 241 and 241' (not shown) thereon which are pivotally mounted on pins 242 and 242' (not shown) which are mounted to brackets 243 and 243' on rotation support members 244 and 244'.

Since members 244 and 244' are substantially identical only one will be described. Member 244 has a body portion 245 (FIG. 6). Extending perpendicular to portion 245 are a pair of vertical plate members 246 which supports a horizontal cover plate 247 and is secured to a bottom member 248 by brackets 249 and bolts 250.

Member 248 has four bolts 251 secured therein, each by nuts 252 and 253. On the top of each bolt are two pair of rollers 254 which are received within tracks, such as 255. L-shaped guides 256 (not shown) are secured to flanges 257 (not shown) on member 248 by means of bolts 258 (not shown). These guides aid in stabilizing the support members as they move on their tracks. The tracks are secured to portions 259 of a frame 201 underlying the drum lifting and rotating mechanism.

Horizontal cover plate 247 has a motor 260 and gear box 261 adjustably secured thereto by plate 262.

Gearbox 261 drives a shaft 263 on which is mounted a double sheave pulley 264. Also mounted on the plate 247, as seen in FIG. 4, are single sheave idler pulleys 266 and 268 on shafts 265 and 267, respectively, and double sheave idler pulley 270 mounted on shaft 269.

Mounted around pulleys 264, 270 and 268 is belt 271 and mounted on pulleys 264, 270 and 266 is belt 272.

The edge of each member 244, 244' nearest the drum is notched as at 273, 274 and 275 (FIG. 4) in its lower plate 248 and has a V-notch such as 276 in a top cover plate 277.

To bring the members 244 and 244' together to engage the side of the drum D with belts 271 and 272 to start it rotating, an air cylinder 280 (FIG. 5) is activated. Cylinder 280 has a piston rod 281 connected to bracket 243' by a pivotable clevis connection 282 and is pivotally connected to bracket 243 by a similar connection.

When cylinder 280 is activated the members 244 and 244' converge toward the drum until the belts 271 and 272 engage the side of the drum.

The operation of the station is as follows. The presence of a drum is sensed by a photocell (not shown). The photocell activates any suitable lifting means (not shown) such as an air cylinder to raise block 216 and rollers R_3 to lift the drum clear of rollers R_1 and R_2 and also energizes air cylinder 280 to move the members 244 and 244' toward the drum. When pressure builds up on the cylinder indicating members 244 and 244' and their belts are against the drum, a pressure actuated switch turns on the drum turner drive motors 260 and resets a printer rotation counter. The printer assemblies are then moved into contact with the drum D by activating air cylinders 109 and 125 in any suitable manner and a proximity switch with cam mechanism counts the rotations of the drum print wheels 116 and 133. When a predetermined number of revolutions of the printer have been counted the operation is stopped. The printing units are removed from engagement with the sides of the drum, the drum turner belts are turned off and the rollers R_3 lower the drum back onto conveyor rollers R_2 which may then be energized to transport the drum away.

While only one embodiment of this invention has been shown and described, it is obvious that many changes and departures will occur to those of ordinary skill in the art within departing from the scope of the appended claims.

What is claimed is:

- 40 1. An automatic drum positioning apparatus comprising a drum conveyor means, lifting means on said conveyor means to raise a drum off of said conveyor means and maintain it in said raised position and means adapted to converge on said drum to rotate the same while said drum is in said raised position; said means to raise said drum coacting with said rotating means to center said drum when said drum is rotated by said rotating means, said lifting means further including a plurality of conically shaped rollers which are disposed so their tips converge and further comprising a vertically movable means on which said tips are supported; said vertically movable means including a block having a plurality of adjacent pairs of rollers extending therefrom, the tips of said conical rollers being of reduced diameter, whereby when said block is raised the tip of each conical roller rides on a pair of said adjacent rollers, and the top surface of the conical rollers are essentially horizontal and above the conveyor rollers.
- 45 2. An apparatus as in claim 1 wherein there are four of said conical rollers in a cross configuration.
- 50 3. An apparatus as in claim 1 wherein said means adapted to converge on a drum to rotate the same comprises a pair of housing members mounted for lateral converging movement, means to move said members together and drum rotation means on each of said members adapted to cooperate to rotate said drum.
- 55 4. An apparatus as in claim 1 wherein the tips of the conical rollers are supported by a block having a plurality of adjacent pairs of rollers extending therefrom, the tips of said conical rollers being of reduced diameter, whereby when said block is raised the tip of each conical roller rides on a pair of said adjacent rollers, and the top surface of the conical rollers are essentially horizontal and above the conveyor rollers.
- 60 5. An apparatus as in claim 1 wherein the tips of the conical rollers are supported by a block having a plurality of adjacent pairs of rollers extending therefrom, the tips of said conical rollers being of reduced diameter, whereby when said block is raised the tip of each conical roller rides on a pair of said adjacent rollers, and the top surface of the conical rollers are essentially horizontal and above the conveyor rollers.
- 65 6. An apparatus as in claim 1 wherein the tips of the conical rollers are supported by a block having a plurality of adjacent pairs of rollers extending therefrom, the tips of said conical rollers being of reduced diameter, whereby when said block is raised the tip of each conical roller rides on a pair of said adjacent rollers, and the top surface of the conical rollers are essentially horizontal and above the conveyor rollers.

4. An apparatus as in claim 3 wherein said means to move said members together comprises a pneumatic cylinder and piston rod, both the piston rod and cylinder being connected to respective ones of said members whereby when said piston rod is retracted, the members converge.

5. An apparatus as in claim 4 wherein said drum rotation means on each said member comprises a driven pulley means and a plurality of idler pulleys, at least one belt being driven around said pulleys.

6. An apparatus as in claim 5 wherein said driven pulley is a double sheave pulley and said idler pulleys comprise a double sheave pulley and two single sheave

pulleys, one belt being trained over one of said single sheave pulleys and both said double sheaved pulleys and a second belt being trained over the other single sheave pulley and the two double sheaved pulleys.

7. An apparatus as in claim 6 wherein portions of each pulley form a V-shaped engagement with the side of a drum, which in conjunction with the heretofore described drum lifting mechanism centers the drum.

10 8. An apparatus as in claim 1 including printing means and means to engage said printing means with said drum includes an air cylinder and crank arm.
